UNITED STATES PATENT OFFICE

FREDERICK A. ANTON, OF TOPEKA, KANSAS

STORE-FRONT AWNING

Application filed November 20, 1928. Serial No. 320,611.

This invention relates to awnings and more especially to display or store front window awnings of that type, known industrially as lateral arm awnings, which employ a roller and jointed arms pivotally connected at one end adjacent the roller and at the other end to the bar or pole at the outer end of the fabric, as exemplified in Patents No. 986,120; 1,069,515; 1,081,882 and 1,118,463, issued to me on March 7, 1911; August 5, 1913; December 16, 1913 and November 24, 1914, respectively.

In all of said patents the construction is such that the inner sections of the arms are pivoted to the bracket in a plane so low that it was necessary that the outer member be folded in a rising or inclined position to dispose the front rod of the awning at or near the top of the roller, as if this were not done too much of the awning, when not in use, was exposed. Such constructions are practical and efficient but they are objectionable in some cases, as they take up too much space vertically measured, and in certain aspects cannot be applied, in many instances, to the newer or modern types of store front constructions.

In the more modern commercial buildings the tendency of architects is to employ narrow transom bars between the customary plate glass window and transom lights, and because of their greater aesthetic appeal, the transom bars are frequently so narrow that it is impossible to equip them with awnings, heretofore available, of the type above mentioned, having the necessary projection or reach and at the same time sufficient pitch to properly shade the window. This problem has given awning companies great concern as frequently calls have been made to equip buildings to which awnings could not be satisfactorily applied. It eventually occurred to me that if the inner sections of the jointed arms could be so arranged that when in folded condition they would be maintained in a

horizontal plane but slightly below the axis of the roller and adjacent the outer surface thereof, it would be possible to dispose the outer sections likewise, and if this could be done, the folded awning would occupy less space, vertically measured, than would be otherwise possible, and enable me to apply an awning to the modern narrow transom bar and at the same time make provision for any spread and pitch desired.

Accordingly I have found that by relatively raising and setting back the pivotally-adjustable arm-supporting bracket in close proximity to the roller, I can provide for the support of the entire arm, when folded, in a horizontal plane but slightly below that of the axis of the roller. This could not be done in a practical manner with the type of hangers and brackets of the prior art patents mentioned, and I accordingly devised a pivotal connection between each hanger and the respective arm-carrying bracket, whereby the pivotal axis of the connection stands in substantial alignment with the inner arm member when the latter is in folded or horizontal position, together with clamping means to maintain the adjustment secured. It was also found desirable to make provision for positively locking the bracket at the requisite adjustment to give the desired pitch to the awning fabric when spread, and I accomplish this also by an adjustable connection between the hanger and bracket. In other respects the structure corresponds in principle and in arrangement to the patented structures hereinbefore identified, and reference is herewith made to such patents for a full understanding of the general construction and mode of operation involved of such common features as not particularly described and shown herein.

There is a large demand for concealed or recess box awning constructions. To provide such type within the height of the modern narrow transom bar, and allow for as much

as a 45° pitch of the fabric, has been heretofore impracticable and to meet this condition, I make the box in a fixed or rear section and a movable or front section, the front one constituting the pole or bar to which the outer or front end of the awning fabric is attached, and to avoid undue width from front to rear of the box and at the same time provide for a complete encasement of the awning when closed, without making the front section of undue weight and size, the bottom of the box is made narrower than the top, and the front section of less height than the fixed section and provided with a rearwardly-projecting flange to abut the front edge of the bottom of the fixed section when the awning is rolled up or closed, the front section thus forming part of the bottom and part of the front of the complete box.

With the object of producing an awning of the type mentioned susceptible of application to the very narrow type of transom bar and for open or concealed use, the invention consists in certain novel and useful features of construction and combinations of parts as hereinafter described and claimed; and in order that it may be fully understood, reference is to be had to the accompanying drawing, in which:

Figure 1 is a fragmentary plan view of a store front awning embodying the invention, the view showing the awning in folded condition in full lines, with the top of the housing or box omitted and the awning fabric broken away.

Figure 2 is a front view of the same, with the awning pole omitted.

Figure 3 is an enlarged section taken on the line III—III of Figure 1, but showing the inner arm member broken away but in unfolded or operative position.

Figure 4 is a sectional view on a still greater scale taken on the line IV—IV of Figure 3.

Figure 5 is a detail perspective view of one of the arm-carrying brackets, and also shows a part of the connection for locking the bracket against accidental movement.

Referring to the drawing in detail, where like reference characters identify corresponding parts in all of the figures, 1 indicates one of a pair of bearing brackets for securement to the transom bar (not shown) of a store front, or to and within a housing or box 2, rigidly secured to a transom bar, the housing or box being shown in this instance as of rectangular form in cross section.

The bearings are for the support of a roller 3 for the awning fabric 4, and if the awning is of substantial length, there will be provided an intermediate roller support of suitable character, that shown comprising a bracket 5 secured to the transom bar or housing and equipped with a series of rollers 6 upon which the fabric around the roller rests, and a roller 7 to overlie the fabric

and cooperate in its guidance as the awning is opened or closed.

For each awning there will be provided two or more foldable arms, each of which consists of an outer member 8 and an inner member 9 operating laterally on the jack-knife principle. Only one set of the arms is shown, and the outer end of each outer member is equipped with a bracket or plate 10 for pivotal connection at 11 with the front pole 12 at the front end or edge of the awning fabric. In the housed type of awning, such as shown herein as distinguished from the unprotected type, the awning pole is preferably in the form of a bar, and said bar as herein-after explained more in detail, conveniently forms a closure for the opening in the housing or box through which the foldable arms and the fabric operate in the opening and closing of the awning.

The inner end of the arm member 8 is equipped with a forked bracket 13 pivotally engaging a bolt 14 carried by a bracket 15 secured to the adjacent end of the inner arm member 9. The inner end of the latter is equipped with a forked bracket 16 pivotally engaging a bolt 17 carried by lugs or ears 18 of a bracket rotatably mounted in a hanger 19 secured to the transom bar or to and within the housing or box, and in this connection it will be noted that the pivot bolts 14 and 17 incline not only in an upward and outward direction, but are also tilted laterally. This inclining or tilting of the pivot bolts is necessary to insure proper operation of the arms in the spreading or closing of the awning, and for guarding against undue frictional contact of the latter with said arms, as explained in connection with the prior art patents hereinbefore identified to which reference is duly made for a full understanding of such operation.

The hanger 19—there will be one for each foldable arm—is formed at its outer end with a horizontally arranged tubular bearing head 20 internally tapered from both ends toward the middle (see Figure 4), and each bracket equipped with lugs 18, has a conical stud 21 which fits in one end and conforms in taper to the enclosing portion of the head 20 and is provided with a cross partition 22 having a central opening engaged by a headed bolt 23. The bolt extends through a corresponding partition in a hollow tapered wedge or plug 24 fitting within the other end of the head and engaging the tapered surface thereof, the wedge being internally tapered to receive the small end of the plug 21. A nut 25 engages the outer end of the bolt and bears against the partition of the wedge for the purpose of clamping the bracket against the inner end of the head and in rigid relation thereto and to the wedge, so that there shall not be any accidental pivotal movement of the bracket on the hanger, it being understood

that rotative adjustment of the bracket on the hanger makes provision for varying the pitch or angle of the curtain, when spread. As a precautionary measure against accidental rotative adjustment, the bracket is provided with a swivelled threaded eye 26 with which is engaged the threaded end of a rod 27, the other end of said rod being reversely threaded and engaging a swivelled threaded eye 28 rigidly secured to the companion hanger. To readily accommodate this locking connection to changes of rotatable adjustment of the bracket, the rod has a plurality of diametric holes 29 wherein a nail can be fitted to turn the rod for the required spacing of the eyes, a nail or the like being the most convenient tool for such purpose as the rod is almost inaccessible to operation by a wrench or pliers.

The pole or bar 12 at the front end of the awning by connection with two or more foldable arm members 8, is maintained in a horizontal position and corresponds in length to the width of the awning fabric. Where the awning is of the protected type, the top of the housing or box preferably terminates in a depending flange or narrow front wall 30, to so reduce the height of the opening through which the awning operates, that the pole or bar 12 shall not be of undue width and weight, and in order that the foldable arms may extend downward and outward to give about a 45° pitch to the awning when spread, the bottom of the housing or box is narrower than the top (see Figure 3), and to compensate for this reduced width, the bar 12 is provided at its lower edge with a rearwardly or inwardly-projecting flange 31 which, when the body of the bar fills and closes the opening, abuts the front edge of the bottom, as shown by Figure 1 and in dotted lines by Figure 3. When thus arranged the only parts exposed are the housing and the customary scalloped drape (not shown) at the front edge of the fabric.

From the above description and the drawing, it will be apparent that I have produced an awning structure which is adaptable by simply varying the length of the arm members 8 and 9, to a store front of any size, and which when folded, takes up so little space, measured vertically or from front to rear or both, that it is applicable to the very narrow transom bars of modern buildings without sacrifice of strength or efficiency. It is also apparent that it is susceptible of minor structural changes within the spirit and scope of the appended claims.

I claim:

1. The combination in an awning, of a suitably journaled horizontally-arranged roller and fabric for winding and unwinding thereon, a rigidly mounted hanger having a horizontal head outward and in the horizontal plane of the lower part of the roller, a hori-

zontal bracket rotatably adjustable around the axis of and secured to said head, a bolt engaging the bracket and inclined upwardly and forwardly and downward and laterally, and a foldable arm pivotally engaged at its rear or inner end with said bolt and adapted to lie substantially horizontal and forward of and parallel with the roller when folded, and when unfolded to extend downward and forward with respect to the roller.

2. The combination in an awning, of a suitably journaled horizontally-arranged roller and fabric for winding and unwinding thereon, a rigidly mounted hanger having a horizontal head outward and in the horizontal plane of the lower part of the roller, a horizontal bracket rotatably adjustable around the axis of and secured to said head, a bolt engaging the bracket and inclined upwardly and forwardly and downward and laterally, and a folding arm, consisting of an inner member pivoted at one end to said bolt, and an outer member pivoted at its inner end to the outer end of the inner member, the pivotal connection for the latter leaning forwardly and laterally to cause the said member to slope downwardly and forwardly when unfolded and to extend horizontally and parallel with the roller when folded, and the pivotal connection between the members being tilted to cause the outer member to extend relatively upward and forward from the inner member when both are unfolded and to extend parallel and in overlapping relation with the inner member when both members are in folded position.

3. The combination in an awning, of a suitably journaled horizontally-arranged roller and fabric for winding and unwinding thereon, a rigidly mounted hanger having a horizontal head outward and in the horizontal plane of the lower part of the roller, a bracket having a horizontal axial stud secured rigidly to and rotatably adjustable on said head, a bolt engaging the bracket and inclined upwardly and forwardly and downwardly and laterally, a foldable arm pivotally engaged at its rear or inner end with said bolt, and adapted to lie substantially horizontal and parallel with the roller when folded and when unfolded to extend downward and forward with respect to the roller, and a pole for the front end or edge of the awning fabric, pivotally attached to the outer end of the foldable arm and adapted when the latter is folded, to extend parallel with, in the same horizontal plane as, and forward of said arm and roller.

4. The combination in an awning, of a horizontally-extending housing having an opening at its front side, a horizontal roller journaled within the box and provided with a fabric for winding and unwinding thereon and for extending forwardly through said opening, an awning pole attached to the front

end of the awning fabric and adapted when the latter is fully wound to occupy said opening and form a front wall for the box, a hanger secured in the box and underlying the roller and provided with a horizontal head forward and in the horizontal plane of the lower part of the roller, a bracket rigidly secured to and rotatably adjustable around a horizontal axis, on said head, a bolt carried by said bracket, and an arm foldable in jack-knife action and pivotally connected at its inner end to said bolt and at its outer end to said pole, and adapted when folded to lie horizontally between the roller and awning pole, and when unfolded, to extend downwardly and forwardly through said opening and below the awning fabric.

5. In an awning structure, the combination of a hanger having a tubular head extending horizontally, of a bracket abutting one end of the head and having a stud projecting rotatably into the latter, a stud abutting the opposite end of the head and projecting thereinto, and clamping means engaging the two studs and exerting force to clamp them rigidly against opposite ends of the head; the said bracket, exteriorly of the head being provided with a pair of spaced lugs and a pivot bolt engaging said lugs and extending upwardly and forwardly and downwardly and laterally, and a foldable arm pivotally engaging said bolt between the bracket lugs and adapted when folded to extend parallel with said studs and when unfolded in a plane intersecting the axis of said studs.

6. In an awning structure, the combination of a vertically-disposed hanger having a horizontally extending head, a bracket abutting one end of said head and provided with a stud projecting into the head, a second stud abutting the opposite end of said head and projecting thereinto, clamping means disposed axially of the head and studs to secure the latter rigidly against opposite ends of the head, a pair of eyes secured to the hanger and bracket respectively, and a rod having reversed screw threaded ends respectively threaded through said eyes for locking the bracket against rotatable movement with respect to the hanger; said eyes being rotatably adjustable to accommodate different rotatable adjustments of the bracket on the hanger.

7. The combination of a horizontal roller and awning fabric wound thereon, a fixed hanger underlying the roller and provided with a horizontal cylindrical head paralleling the roller, and occupying a point forward but in the same horizontal plane as the lower part of the roller, a bracket fitting against and clamped to the head for rotative adjustment in a vertical plane and provided with upper and lower lugs, a folding arm, pivoted at its inner end to and between said lugs for

swinging in a plane intersecting that of the rotative adjustment of the bracket, and a bar attached to the outer end of the fabric and pivotally connected to the outer end of the folding arm and adapted when the latter is folded and the awning is closed, to extend horizontally forward of and in proximity to and in the same horizontal plane as the folded arm.

In testimony whereof I affix my signature.
